UNITED STATES PATENT OFFICE.

ALBERT FISS, OF ST. LOUIS, MISSOURI, ASSIGNOR TO THE A. FISS COMPANY, OF ST. LOUIS, MISSOURI, A CORPORATION OF MISSOURI.

TOOL BOX.

Application filed February 17, 1927. Serial No. 168,852.

This invention relates to tool boxes for attachment to the running board and fender of automobiles.

An object of the invention is to provide a tool box of an improved construction designed and shaped to fit upon adjacent portions of a running board and fender and provided with means for preventing rattling and for maintaining rigid connection with the running board and fender.

Other objects of the invention will appear from the following description, reference being made to the drawing, in which

Fig. 1 is a side elevation of my improved tool box seated upon the running board and fender of an automobile and showing the relationship of the tool box to the automobile structure, including a swinging door.

Fig. 2 is a cross sectional view on the line 2—2 of Fig. 1.

Fig. 3 is a longitudinal vertical sectional view of the tool box showing the fasteners for holding the tool box in connection with the running board and fender of the automobile.

Fig. 4 is an enlarged sectional view showing the fastening device and its connection with the tool box and the running board.

Fig. 5 is a vertical sectional view of the upper portion of one of the side walls.

Fig. 6 is a sectional view of a portion of the cover.

My improved tool box comprises a pair of metallic side walls 1, a metallic rear end wall 2 and a metallic front end wall 3. The abutting ends of these side and end walls are in rigid connection with vertical angle corner pieces 4, whereby rigidity is obtained. The lower front corners of the side walls 1 are rounded in conformity with the curvature of the rear portion of the front fender of the automobile for which the device is constructed. Thus, the front end wall 3 extends downwardly only about one-half of the vertical width of the rear end wall 2.

The enclosure formed by these side and end walls has a non-metallic lining comprising parts 5 for the side walls 1, a part 6 for the end wall 2 and a part 7 for the front wall 3. The upper edges of the walls 1, 2 and 3 extend over the upper edges of the lining pieces and are attached thereto by

fasteners 8 driven through the indent edges of the metallic walls and into the non-metallic lining. The lower edge of the wall 3 is rebent as shown at 9 to form a channel confining the lower edge of said wall 3 (Fig. 3).

I provide a metallic bottom wall 10 formed with a depending flange 11 extending along its rear and side edges. This flange 11 extends downwardly to the plane of the lower edges of the rear end and side walls and forms a reinforcement strengthening the structure, and numerous tacks or other appropriate fastening elements 12 are driven through the flange 11 and into the composite wall structure of the box as described. There is no depending flange such as 11 across the front end of the bottom 10, but the front end of the bottom 10 extends upwardly against the inner side of the rebent portion 9 of the front metallic wall 3.

A channelled strip of rubber or other elastic material 13 encloses the lower edges of the rear end and side walls and is attached thereto by fasteners 14 driven through the rubber and into the lining of the box. In use, this rubber rests upon the upper sides of the running board and adjacent curved portion of the fender and prevents noise that would result if the metallic parts of the box rested upon the metallic parts of the automobile and also prevents the box from defacing the polished surfaces of the automobile.

An angular metallic element 15 has one arm seated upon the rear portion of the bottom 10 of the box and the other arm extending vertically and rigidly attached to the rear end wall. The bottom 10 and the superimposed arm of the angle piece 15 have holes therethrough. A fastening bolt 16 extends vertically through the running board structure 17 and through the holes in the bottom wall 10 and angle piece 15. The head of this bolt is at the underside of the running board while the nut is secured on the bolt in the box. Preferably a rounded head bolt is used so as to render it difficult to remove the bolt from the outside.

A reinforcing plate 18 is attached to the front end wall of the box and extends downwardly over the front end of the bottom 10. A bolt 19 passes through the fender 20 and through holes in the bottom wall 10 and the

plate 18, the nut of this bolt being on the inside of the box to prevent removal of the bolt from the outside.

The front and rear end walls of this box have transverse strips 21 attached thereto supporting a removable tray 22 divided into a number of compartments by partitions 23 and designed and adapted to contain small tools and parts, such as pliers, screw drivers, 10 small wrenches, spark plugs, etc. This tray is preferably made of wood to reduce noise.

The cover for my improved box as shown comprises a top wall 24 of wood or the like covered on the outside by a layer of rubber 15 or other appropriate material 25 and reinforced at the edges by metallic angle members 26 having horizontal flanges attached to the underside of the top and having vertical flanges designed and arranged to enclose the 20 upper portion of the box when the cover is closed. The border for this cover comprises metallic angular pieces 27 having horizontal flanges engaging upon the part 25 and vertical flanges enclosing the edges of the cover 25 and extending downwardly nearly as far as the vertical flanges of the angle pieces 26. The inner edge of this cover is secured to the box by hinges 28 and the outer edge of the cover is provided with a lock 29.

This improved box possesses numerous advantages over those with which I am familiar and constitutes a highly useful and ornamental accessory for an automobile. This box may be easily attached to the automobile in a 35 convenient position, permitting the door of the automobile to open without interfering with the box. The metallic outer walls of the box are capable of being highly polished in conformity with the polished surfaces of 40 the automobile and the wooden or non-metallic lining of the box prevents noise. The space between the bottom wall 10 and the fender and running board of the automobile is a noise absorbing space. Another 45 advantage in having the metallic bottom wall 10 above and out of contact with the metallic portions of the automobile exists in the fact that creaking and other noises are eliminated and the likelihood of corrosion 50 and rusting of the parts is diminished. It also permits this device to be applied readily to automobiles having fenders of the type in which the longitudinal central portion is raised or curved upwardly forming a longitudinal crown.

I am aware that the device may be varied in particulars other than those specifically

mentioned and do not restrict myself un- 60 essentially, but what I claim and desire to secure by Letters Patent is:—

1. A tool box of the character described comprising metallic outer walls, a non-metallic lining secured to said walls, a metallic bottom between said outer walls and above the lower edges thereof, a flange on said bottom extending downwardly against the inner surface of said lining, an elastic cushion enclosing the lower edges of said walls and said flange, reinforcing elements within the box adjacent to said bottom wall, and fasteners 70 passing through the bottom wall and through said elements and holding the box in rigid position.

2. A tool box arranged to seat upon the running board and adjacent curved portion 75 of the front fender of an automobile comprising side and end walls forming an enclosure and shaped at one end to conform to the curvature of the automobile fender adjacent to the running board, a metallic bottom wall for said box having one end curving as aforesaid, metallic strengthening elements within the box adjacent to the ends of the bottom wall, and fasteners passing through the fender and the running board 80 respectively and through said bottom wall and said elements and holding the box rigid.

3. A tool box arranged to seat upon the running board and adjacent curved portion 85 of the front fender of an automobile comprising side and end walls forming an enclosure and shaped at one end to conform to the curvature of the automobile fender adjacent to the running board, a metallic bottom wall for said box having one end curving as aforesaid, metallic strengthening elements within the box adjacent to the ends of the bottom wall, fasteners passing through the fender and the running board respectively and through said bottom wall and 90 said elements and holding the box rigid, and elastic cushions enclosing the lower edges of said side walls and one of said end walls and bearing upon the running board 95 and fender.

4. A tool box comprising side and end walls, a bottom wall between the side and end walls and above the lower edges thereof, an elastic cushion enclosing the lower edges of said side walls and one of said end walls, and clamping means passing through the bottom wall of the box and securing the 100 box rigidly upon its support.

ALBERT FISS.
